E. J. MORDT

REEL

Filed Aug. 18, 1924

FIG. 1.

FIG. 2.

Inventor.
Erik J. Mordt
By Glenn S. Noble, Atty.

UNITED STATES PATENT OFFICE.

ERIK J. MORDT, OF EVANSTON, ILLINOIS.

REEL.

Application filed August 18, 1924. Serial No. 732,770.

To all whom it may concern:

Be it known that I, ERIK J. MORDT, a citizen of the United States, residing at Evanston, in the county of Cook and State 5 of Illinois, have invented certain new and useful Improvements in Reels, of which the following is a specification.

This invention relates to reels adapted for winding rope, twine, cord, line or the like 10 and is particularly intended for use in connection with clothes lines. Clothes lines are usually wound in hanks for selling and the user after unwinding the hank commonly winds the rope or line up in a ball or in a 15 roll and in doing so the line is usually twisted until it becomes full of kinks and in some cases the twisting action takes the twist or lay out of a twisted rope so that the strands are more or less parallel and the 20 rope is thereby more or less injured.

My invention provides a combined holder and reel which serves as a means for holding or supporting the rope in attractive 25 position for selling or merchandising and also provides means whereby the rope will be better preserved and is more readily handled when it is put in use.

The objects of this invention are to provide an improved reel for rope, twine or the 30 like; to provide a reel which will be light, strong and simple in construction and which may be manufactured at a low cost; to provide a reel of this character which will be durable and efficient in operation and also 35 which will be attractive in order to provide a holder which will assist in merchandising clothes lines or other similar lines; and in general to provide such an improved device as will be described more fully hereinafter.

40 In the accompanying drawings illustrating this invention,

Figure 1 is a side view of a reel or holder showing a portion of the line wound thereon; and

45 Figure 2 is an end view of the same.

In the particular form of the invention as illustrated in these drawings, the reel comprises a frame or holding portion 3 which is provided with suitable handles 4 and 5 whereby it may be supported in one hand of the operator and turned by the other hand. The holder or frame portion 3 is preferably made flat so that it will occupy but little space and in the present instance 50 is shown as made of wire bent to form sides 6-6 and ends 7-7 which are con-

nected by loops 8-8. These loops form the flanges or rope retaining side portions of the reel. This frame member or holder may be made of a single piece of wire or for convenience in construction it may be 60 made of two pieces with the abutting ends welded or fastened together.

The handles 4 and 5 are carried on a rod or wire 9. One end of this wire projects at right angles to the frame in the center thereof to receive the handle 4 and the wire is then bent and carried up to a point adjacent to one end of the frame where it projects at right angles thereto to receive the handle 5. This rod or wire is secured to the frame 70 portion 3 by welding, brazing or in any other suitable manner. The rope or clothes line 10 is secured to the rod 9 by a clip 11 and is wound over the end pieces 7 until a sufficient amount is reeled thereon. When a 75 close line, for instance, has been wound on the reel it presents a particularly neat and attractive appearance and if desired the end of the line may be provided with a loop which will be exposed on the face of the 80 coil so that the purchaser will see that the end of the line may be fastened to a hook or nail without having to be tied. Furthermore, I prefer to have the frame or reel 85 painted or enamelled in attractive colors thereby forming a colored frame around the reeled line which further adds to the appearance of the device and assists in merchandising such lines. When the line is to be unreeled, the operator fastens the free 90 end to a hook, nail or the like and by holding on the handle 4 the reel will readily rotate to pay off the line. When the line is to be again wound up, the operator holds the handle 4, for instance, in the left hand 95 which serves as a bearing and the handle 5 then serves as a crank handle for turning the reel.

It will of course be apparent that the device may be made in various sizes and 100 shapes for displaying and reeling different kinds of lines, rope, cord or the like without departing from the scope of my invention and therefore I do not wish to be limited to the exact form herein shown and 105 described, except as specified in the following claims in which I claim:

1. A reel comprising a rectangular frame with sides 6-6 and ends 7-7 connected by integrally formed flanges 8, a wire 9 secured 110 to the frame and having one end projecting

from the frame in the center thereof and the other end projecting from the other side of the frame at a distance from the center and rotatable handles secured to said projecting ends.

2. A reel comprising a frame formed of wire with projections at the corners for retaining a line to be reeled thereon, a wire arranged diagonally with respect to the frame and having one end projecting at the center of the frame and the other end at a distance from the center and rotatable handles secured to the projecting ends.
- 10

3. In a device of the character set forth, the combination of a reel comprising a flat 15 frame formed of wire having depressions in the end thereof for receiving the rope to be reeled thereon, a cross piece secured to said frame and having its ends projecting at either side of the frame, handles secured 20 to said ends and a rope having one end secured to said cross piece and being adapted to be reeled upon the frame, substantially as described.

ERIK J. MORDT.
